UNITED STATES PATENT OFFICE.

UTLEY WEDGE, OF PAOLI, PENNSYLVANIA.

AIR BLOWER OF THE CAGNIARDELLE TYPE.

Application filed April 21, 1925. Serial No. 24,719.

To all whom it may concern:

Be it known that I, UTLEY WEDGE, a citizen of the United States, residing at Paoli, in the county of Chester and State of Pennsylvania, have invented a new and useful Improvement in Air Blowers of the Cagniardelle Type, of which the following is a specification.

The "Cagniardelle" type of blower is so called from its inventor, Cagniard Latour, and a good description of it may be found on page 60 of Vol. XVI. of the New Werner Ed. Encyclopædia Britannica, published by the Werner Company, New York, Akron and Chicago, 1901.

The principal object of the present invention is to increase the capacity of the "Cagniardelle" type of air blower and in one of its aspects this invention comprises the provision of either or both of two paths for the escape of water in addition to the path ordinarily provided at the discharge end of the casing, which path, when present, is necessarily contracted in order to provide a sufficient depth of liquid seal for opposing the escape of air. In another of its aspects the invention comprises the provision of ports in the external wall of the casing between its ends and the adaptation and utilization of an endless belt for covering the portions of those ports that are exposed to the air and uncovering the portions of those parts that are submerged.

The invention will be claimed at the end hereof but will be first described in connection with the embodiment of it chosen from among other embodiments for the sake of illustration in the accompanying drawings.

In the drawings—

Figure 1 is a view, partly in central section and partly in elevation, of an air blower of the "Cagniardelle" type embodying features of the invention.

Fig. 2 is a sectional view taken on the line 2—2 of Figure 1 looking in the direction of the arrows.

Fig. 3 is a central sectional view illustrating a modification, and

Fig. 4 is a transverse sectional view taken on the line 4—4 of Fig. 3.

In the drawings 1, generally, is a rotatable casing internally provided with a water spiral or Archimedean screw element 2 and having a contracted end outlet 3 that affords a path for the escape of water.

The end 3 is contracted in order to provide an appropriate depth of seal for preventing the escape of air except by way of the off-take 4. As usual air enters the casing at the open end 3^a thereof. 5 is a water tank in which the casing 1 is partially submerged and rotated. The foregoing description merely indicates features of the "Cagniardelle" type of blower upon which my invention is an improvement, and a description of my invention will now be given. The external wall 6 of the casing 1 is ported between the ends of the water spiral or Archimedean screw element 2, for example, as at 7. The internal wall 8 of the casing is also ported between the ends of the water spiral or Archimedean screw element. This internal wall of the casing is also the bounding wall of a drum 9, closed at its ends 10. The ports in this wall 8 are indicated at 11 and they are disposed between the flights of the screw 2. 12 is a band or belt shown as of the endless variety and it is adapted to cover the ports 7. Referring to Fig. 2, 13 are guide pulleys and 14 is a belt tightener and their purpose is to run a reach of the belt 12 in contact with the exposed portions of the ports 7 to cover them against the passage of air and to run the belt out of contact with submerged portions of the ports 7 to uncover them and provide a path for the escape of water supplemental to the path for the escape of water provided by the contracted end outlet 3, when present. The ports 11 and drum 9 permit of the circulation of water between the flights of the screw and in that way constitute another path for the escape of water which is supplemental to the path provided by the ports 7 and to the path provided by the outlet 3. In the modification, Fig. 4, the belt 12^a, is guided by a single guide pulley 13^a and is tightened by the guide pulley 14^a. As shown the belt is driven from a pulley 15 through a countershaft 16 and belt 17, and the countershaft 16 serves to revolve the pulley over which the belt passes, and in such case the belt serves to rotate the casing and water spiral or Archimedean screw element as a whole. However, that is not important in all cases but the belt and the surface of the casing should run at substantially the same lineal speed. The level of the water in the tank 5 is indicated at α . By my improvements the capacity of the "Cagniardelle" type of air blower is in-

creased by the provision of one or more paths for the escape of water from the interior of the casing supplemental to the outlet 3 which, as has been said, when present 5 is necessarily restricted in order to provide an air seal of sufficient depth to be effective. Reference is made to water as the liquid contained in the tank 5, but I intend to include also other liquids or fluids within that 10 term.

It may be remarked that when the ports 11 are provided it is necessary to submerge the drum 9 in the fluid in the tank sufficiently to loot the ports 11 in order to prevent 15 the escape of gas.

It will be obvious to those skilled in the art to which the invention relates that modifications may be made in details of construction and arrangement without departing 20 from the spirit of the invention which is not limited as to those matters or otherwise than as the prior art and the appended claims may require.

I claim:

- 25 1. An air blower of the "Cagniardelle" type having a rotatable spiral or Archimedean screw element including a casing wall ported between the ends of said element to afford a path for liquid.
- 30 2. An air blower of the "Cagniardelle" type having a rotatable spiral or Archimedean screw element including a casing having end openings of which one is constricted and having between the ends of said element 35 a ported outer casing wall affording a path for the escape of liquid supplemental to the path for the escape of liquid provided by the constricted end opening.
- 35 3. An air blower of the "Cagniardelle" type including in combination a peripherally ported rotatable casing internally provided with a spiral or Archimedean screw element, a tank for liquid in which the casing is partially submerged, and a band or 45 belt running in contact with the exposed portion of the outer surface of the casing to cover the ports against the passage of air and clearing a submerged portion of the outer surface of the casing to uncover the 50 ports and provide a path for the escape of liquid.
- 45 4. An air blower of the "Cagniardelle" type including in combination a peripherally ported rotatable casing internally provided with a spiral or Archimedean screw element, a tank for liquid in which the drum 55 is partially submerged, and means for covering the exposed portion of the ports against the passage of air and for uncovering a submerged portion of the ports to provide a path for the escape of liquid.
- 60 5. An air blower of the "Cagniardelle"

type including in combination a rotatable casing contracted at its discharge end and provided with an external ported casing 65 wall and with an internal ported drum wall and having mounted therein and between said walls a spiral or Archimedean screw element, a tank for liquid in which the casing is partially submerged, and means for 70 covering the ports at the exposed portion of the external wall and for uncovering the ports at a submerged portion of the external wall.

6. An air blower of the "Cagniardelle" 75 type including in combination a rotatable casing contracted at its discharge end and provided with an external ported casing wall and with an internal ported drum wall and having mounted therein and between 80 said walls a spiral or Archimedean screw element, a tank for liquid in which the casing is partially submerged, and an endless band or belt running in contact with the exposed portion of the external casing wall 85 to cover the ports against the passage of air and clearing a submerged portion of the external casing wall to uncover the ports and provide for the escape of liquid.

7. An air blower of the "Cagniardelle" 90 type including in combination a peripherally ported rotatable casing internally provided with a spiral or Archimedean screw element and having a contracted end outlet, a tank for liquid in which said casing is 95 partially submerged, an endless band or belt adapted to cover said ports, and pulleys for guiding said belt in contact with the exposed portion of said ports to cover them against the passage of air and out of contact with 100 a submerged portion of said ports to uncover them and provide a path for the escape of liquid supplemental to the path for the escape of liquid provided by said contracted end outlet.

8. An air blower of the "Cagniardelle" 105 type having a rotatable spiral or Archimedean screw element including a casing having three paths for the escape of water of which one is a contracted opening provided at one end of the casing and of which another is a port provided at the periphery of the casing and of which the third is a centrally arranged drum communicating with the space between the flights of the screw 110 or spiral.

9. An air blower of the "Cagniardelle" 115 type having a rotatable spiral or Archimedean screw element including a casing having a peripheral port and provided with an endless band running partway around the casing to cover and uncover said port.
